TONGS

James P. Ratigan, Los Angeles, Calif.

Application July 20, 1932. Serial No. 623,513

1 Claim. (Cl. 81—99)

This invention relates to tongs and the like.

An object of this invention is to provide a new and improved tongs adapted to be easily handled and of great strength but light weight, the elements of which are so constructed and disposed that the tongs quickly, automatically and securely grips the pipe or other object to which it is applied, but may readily be removed therefrom.

A further object is to provide a new and improved tongs adapted to automatically hold itself on a vertical pipe or the like.

A further object is to provide a tongs embodying bits forming teeth and a new and improved means for mounting the bits in the tongs.

15 A further object is to provide means for securely and inexpensively locking the bits in the tongs, which means do not weaken the tongs.

A further object is to provide a tongs with removable jaws in order that jaws of different sizes 20 may be mounted in the tongs to enable the tongs to operate upon a wide range of pipe sizes.

A further object is to provide means for yieldingly urging the jaw into closed position.

A further object is to provide a tongs which 25 is sturdy and inexpensive to manufacture and a tool which has a wide range of utility.

Other objects and advantages of the invention will become apparent as the nature of the same is more fully understood from the following detailed description and accompanying drawing, wherein is set forth what is now considered to be a preferred embodiment. It should be understood, however, that this particular embodiment of the invention is chosen principally for the 35 purpose of exemplification, and that variations therefrom in details of construction or arrangement of the parts may accordingly be effected and yet remain within the spirit and scope of the invention as the same is set forth in the appended 40 claim.

In the drawing:

Figure 1 illustrates a plan view of the invention partly in section.

Figure 2 illustrates a side view of Figure 1.

45 Figure 3 illustrates one of the removable jaws for a larger size pipe, which may be mounted in the handle of the tongs.

Figure 4 illustrates an enlarged sectional view taken substantially along line 4—4 of Figure 1.

50 Figure 5 illustrates an enlarged sectional view illustrating the section of the removable jaw as taken substantially along line 5—5 of Figure 1.

In the preferred embodiment of my invention illustrated in the drawing, the tongs may include 55 a handle 1 preferably of cast steel. The handle

may be cored out as at 2 for sake of lightness, and may be provided with square openings 3 of different sizes whereby the handle may be conveniently used as a wrench. At one end the handle may be bifurcated as at 4 to receive the 60 movable jaw 5, also preferably made of cast steel. The movable jaw 5 is pivotally mounted in the bifurcated end of the handle by means of a common bolt 6.

A transverse bore 7 may be cored into the 65 handle adjacent the bifurcated end thereof, which cored bore may be machined out to receive spring 8 and plunger 9. Preferably the transverse bore 7 is closed at one end to form a seat for the spring.

The movable jaw may be provided with a lug 10 which lug may extend into the transverse bore 7, through the opening 11 formed between the bore and bifurcated section of the handle, and positioned to be acted upon by the spring for 75 yieldingly holding the movable jaw in closed relation with the handle.

The handle may be provided with any suitable form of stop means for preventing the movable jaw from closing beyond a predetermined point. 80 The stop means illustrated in Figure 1 includes a bridging piece 12 for spanning the bifurcated portion of the handle adjacent the opening 11 through which the lug 10 extends and is positioned to be engaged by the lug when the movable 85 jaw has closed to a predetermined position. The bridging piece 12 also acts as a brace member for stiffening the bifurcated section.

As stated, the movable jaw may be preferably made of a steel casting and formed for the most 90 part of an H section as illustrated in Figure 5. The section of the jaw which fits between the bifurcated section of the handle is just thick enough to make a nice working fit and it is from this section that the lug 10 projects. The lug 95 10 is preferably cast integral with the jaw.

Square bits or teeth 13 are removably mounted in the jaw in such a manner that one corner of each bit projects radially toward the center of the jaw. The mounting of the bits is one of 100 the important features of this invention, and for this purpose square slots 14 are cast transversely of the jaw. As will be noted from Figure 4, the bit slots 14 may be cast nearly all the way across the jaw so as to leave a seat against which the 105 inner end of the bit may seat; or, as illustrated in Figure 4, the bit slots may extend the full width of the jaw and a flange 15 may be provided to form the bit seat. In most cases the cored bit slots are sufficiently accurate so that 110

the bits may be assembled without the necessity of machining these slots, however, in some cases the slots will require to be slightly broached to remove irregularities.

5 In order to lock the bits in the bit slots, a stud 16 may be cast integral with the jaw or welded thereto adjacent each bit slot (note Figure 4).

In actual practice I have found that the studs are cast very nearly to size and therefore may 10 be very easily machined to size with an ordinary box tool and then threaded. By screwing a common square nut 17 upon each stud, the body portion of the nut will extend over the bit slot and thereby lock the bit securely in position. One of 15 the important advantages of providing the integral studs 16 is that the jaw section is not weakened as would be the case should a hole be drilled into the jaw and threaded to receive a locking screw.

20 The end of the jaw may be provided with a nail pulling slot 17 to render the tool more adaptable for all around use.

Another important feature of my invention is 25 to provide a handle adaptable for receiving different size jaws as for example in Figure 1 the handle is provided with a small jaw, but this jaw may be easily and readily removed by removing the common bolt 6 and then mounting the relatively large jaw 18 illustrated in Figure 3. In 30 actual practice I find that with one handle unit I am able to successfully mount jaws ranging from 1½ inch to 3 inches, thus rendering a single handle and set of jaws operable for a very wide range of pipe sizes. And therefore, with my invention, an operator need not buy a series of 35 complete tongs for each size of pipe.

The handle is provided with a bit 19 spaced a predetermined distance from the pivot bolt 6, and as it is this distance which determines the 40 leverage of the tongs, the leverage remains constant for each size of jaw mounted in the handle, which is an important advantage.

The bit 19 may be mounted in the handle in the same manner as the bits 13 are mounted in the movable jaw.

In operating the tool, the proper size jaw will be selected for the size of work and mounted in 80 the handle by means of the pivot bolt 6. For each size jaw the spring 8 acts through plunger 9 to hold the movable jaw in its closed position by yielding acting against the lug 10. For each size jaw the bridging piece 12 acts to gage the 85 closed position of the jaw.

As will be noted from Figure 1, the entrance to the tongs is tapered to facilitate the mounting of the tongs upon the pipe. Once the tongs are mounted upon the pipe, they will remain clamped 90 thereon, due to the action of the spring means urging the jaw against the pipe.

Should one of the bits become dulled, it may be easily withdrawn from the slot by first removing the locking nut 17 and then sliding the bit 95 free of the slot, whereupon the bit may be replaced by a new one or may be turned to present a new corner to the pipe.

From the description and drawing, it will be observed that I have invented a tool adapted for 100 use over a wide range of sizes, and a tool which is very simple, sturdy and inexpensive of manufacture and also a tool which has a wide range of utility.

Having fully described my invention, it is to be 105 understood that I do not wish to be limited to the details herein set forth, but my invention is of the full scope of the appended claim.

I claim:

The mounting for a bit in a tong, including a 110 tong having a bit slot, a flange closing one end, of the bit slot, a stud cast integral with said tong adjacent said slot and screw-threaded, a bit mounted in the slot, and a nut screw-threaded upon the stud for effectively sealing the bit in 115 the slot.
